UNITED STATES PATENT OFFICE.

BURRELL CANNON, OF LONGVIEW, TEXAS.

APPARATUS FOR AUTOMATICALLY PHOTOGRAPHING PERSONS MOVING ALONG A CONFINED WAY.

1,105,484.

Specification of Letters Patent.

Patented July 28, 1914.

Application filed June 4, 1913. Serial No. 771,759.

To all whom it may concern:

Be it known that I, BURRELL CANNON, a citizen of the United States, resident of Longview, in the county of Gregg and State 5 of Texas, have made a certain new and useful Invention in Apparatus for Automatically Photographing Persons Moving Along a Confined Way; and I declare the following to be a full, clear, and exact description 10 of the same, such as will enable others skilled in the art to which it appertains to make and use the invention, reference being had to the accompanying drawings, and to letters or figures of reference marked thereon, 15 which form a part of this specification.

Figure 1 is a side view of the invention as applied to a railway car. Fig. 2 is a side view of the invention partly in section and partly broken away. Fig. 3 is a detail plan view. 20 The invention has relation to apparatus or means for counting or checking fares or persons by photography, designed to automatically photograph all persons entering a place, building or vehicle where fares or 25 tickets of admission are collected; or it may be in some cases to photograph persons leaving the place or vehicle.

The invention consists in the novel construction and combinations of devices here- 30 inafter set forth.

In the accompanying drawings, illustrating the invention, the numeral 1 designates a camera, wherein the reel 2, carrying the film, is operated in a step by step manner by 35 persons entering or leaving, to expose new portions of the film, a shutter 3 of the camera being also operated to expose the particular portion of the film upon which the picture is taken.

40 The means of operation consists preferably of a mat 4, placed in the entrance or exit, so that all persons passing through will necessarily step thereupon, said mat being of air tight character and provided 45 usually with springs 5, to maintain the cover part of the mat in normal raised position; a tube 6 leading from the interior of the mat, and having at its opposite end communication with a cylinder 7, wherein

works a piston 8, the piston rod 9 having 50 suitable operating connections with the shutter of the camera and with the film-carrying reel, so that the shutter will be first operated and afterward the reel, upon the same stroke of the piston to move the 55 film, to expose a different portion thereof upon the succeeding movement of the shutter, the film being moved at intermediate times to the movement of the shutter.

The mat being compressed by the weight 60 of the person stepping thereupon, the air is caused to pass through the tube into the cylinder and operate the piston. When the person steps from the mat, the springs will raise the cover of the mat to normal raised 65 position and a new portion of air will be admitted to the mat through an air inlet opening 10. Usually the film carrying roller will have a ratchet wheel 11, the pawl 12 of which will be operated to turn the 70 roller and cause the film to move by an operating connection with the piston rod.

The camera may be placed to take either a front or a profile picture, and at night or upon dark days, a suitable light may be 75 used.

It will be obvious that the invention may be carried out by different mechanisms, but the means described is preferred.

In some cases a calendar clock may be 80 used with cards to show the number and direction of a railway train, in proper position to appear in every photograph.

A station indicator may be used showing the next stop, to appear in every photo- 85 graph, and when the photographs are taken of both entering and departing passengers, a perfect record will be kept.

What I claim is:—

Apparatus for photographing persons 90 moving along a confined way, consisting of a camera having rollers and a film carried by said rollers, said camera having its lens in position to photograph persons moving along said way, and automatically-resetting 95 means in said way having an operating connection with the shutter and with a film-carrying roller of the camera, said means

being adapted to be successively actuated by persons moving along said way to successively move said shutter and expose a portion of the film, and at intermediate times to 5 successively move said film to expose a different portion thereof upon the succeeding movement of said shutter.

In testimony whereof I affix my signature, in presence of two witnesses.

BURRELL CANNON.
